UNITED STATES PATENT OFFICE.

MARTIN SCHICHTL, OF NORTH YAKIMA, WASHINGTON.

POLE-SUPPORT.

SPECIFICATION forming part of Letters Patent No. 637,036, dated November 14, 1899.

Application filed August 1, 1899. Serial No. 725,804. (No model.)

To all whom it may concern:

Be it known that I, MARTIN SCHICHTL, a citizen of the United States, residing at North Yakima, in the county of Yakima and State of Washington, have invented a new and useful Pole-Support, of which the following is a specification.

The invention relates to improvements in pole-supports.

- 10 The object of the present invention is to improve the construction of pole-supports and to provide a simple, inexpensive, and efficient device adapted to be readily applied to the running-gear of a vehicle and capable 15 of yieldingly supporting the tongue or pole in an approximately horizontal position and of relieving the necks of the horses or other draft-animals of the weight of the said tongue or pole.
- 20 A further object of the invention is to provide a device of this character which may be readily adjusted to vary the tension of the spring and arrange the pole or tongue in the proper position.

25 The invention consists in the construction and novel combination and arrangement of parts hereinafter fully described, illustrated in the accompanying drawings, and pointed out in the claims hereto appended.

30 In the drawings, Figure 1 is a perspective view of a portion of a running-gear provided with a pole-support constructed in accordance with this invention. Fig. 2 is a longitudinal sectional view of the same. Fig. 3 is 35 a detail perspective view of the clamp. Fig. 4 is a horizontal sectional view of the clamp.

Like numerals of reference designate corresponding parts in the several figures of the drawings.

40 1 designates a telescoping connection extending from the tongue or pole 2 of a running-gear to the front axle 3 of the same and composed of a rod 4 and a tube 5, receiving the inner portion of the rod. The tube and 45 the rod form an extensible connection which is adapted to yield to the vibration of the tongue or pole, and this vibration is cushioned by a spiral spring 6 of sufficient strength to sustain the weight of the pole and is disposed on the rod 4 and interposed between 50 the front end of the tube and an adjustable

collar 7. The collar, which is arranged on the rod, is secured to the same by a clamping-screw 8 and is adapted to be moved toward and from the front end of the tube to 55 vary the tension of the spring.

The front end of the rod 4 is provided with an eye 9, which is pivoted by a bolt 10 or other suitable fastening device in a bifurcation 11 of the rear end of a plate or piece 12, 60 which is secured to the lower face of the tongue, whereby the extensible connecting device is hinged to the same. The rear end of the tube 5 is provided with a T-shaped coupling 13, which has its transverse portion 65 14 pivoted to the sides 15 of a clamp 16 by a transverse bolt 17 or other suitable fastening device. The bolt 17 is arranged at the front portion of the clamp, and the sides 15, which are substantially U-shaped, are connected at 70 the back by a bolt 18 and are spaced apart by a sleeve 19, disposed on the said bolt 18 and interposed between the sides 15. The sleeve or eye formed by the transverse portion of the T-shaped coupling and the bolt 75 17 form a hinge-joint between the lower end of the tube and the clamp.

The substantially U-shaped sides of the clamp have approximately vertical arms 20 arranged at the front and rear faces of the 80 front axle and terminating in horizontal eyes 21, which are interiorly threaded for the reception of horizontally-disposed clamping-screws 22, adapted to engage the front and rear faces of the axle 3, as clearly illustrated 85 in Fig. 2 of the accompanying drawings, whereby the device is mounted on the said axle. The arms receive the axle between them and are adapted to be readily arranged on the same without necessitating any alteration in the construction of the running-gear.

It will be seen that the device, which is simple, inexpensive, strong, and durable, is arranged centrally beneath the rear portion of the pole or tongue and is hinged to the same 95 and to the front axle and that it is adapted to yieldingly support the former and relieve the necks of the horses or other draft-animals of strain. It will also be apparent that the device is adapted to be readily applied to any 100 ordinary vehicle, and that the parts are readily adjustable to vary the tension of the spring

and arrange the pole or tongue in the desired position, and that it will permit the same to have a limited vibration.

Changes in the form, proportion, size, and the minor details of construction within the scope of the appended claims may be resorted to without departing from the spirit or sacrificing any of the advantages of this invention.

What is claimed is—

- 10 1. In a device of the class described, the combination with a running-gear, of a clamp detachably engaging the front and rear faces of the front axle, an extensible telescoping section hinged to the clamp, means for hinging the connection to a pole or tongue, and a spring cushioning the extensible connection, substantially as described.
- 15 2. In a device of the class described, the combination with a running-gear, of a substantially **U**-shaped clamp receiving the front axle and detachably engaging the front and
- 20

rear faces of the same, an extensible connection hinged to the clamp and to the tongue, and a spring cushioning the connection, substantially as described.

25 3. A device of the class described comprising a clamp composed of two substantially **U**-shaped sides provided at their terminals with clamping-screws for engaging the front and rear faces of the front axle and connected by 30 transverse fastening devices, and an extensible cushioned connection designed to be hinged to a tongue and provided with a sleeve receiving one of the said transverse fastening devices, substantially as described.

35 In testimony that I claim the foregoing as my own I have hereto affixed my signature in the presence of two witnesses.

MARTIN SCHICHTL.
